CLAIM

The ornamental design for a chessmen set, as shown and described.

DESCRIPTION

FIG. 1 is an elevational top view of the chessmen set showing our new design;

FIG. 2 is right and left side view, both of which are mirror images, thereof;

FIG. 3 is a front side view, thereof; and,

FIG. 4 is a rear side view, thereof.

The bottom view of the design is flat and includes no ornamentality.
